[57] CLAIM

The ornamental design for an inflatable saddle for an aquatic game, as shown.

DESCRIPTION

FIG. 1 is a perspective view of the inflatable saddle for an aquatic game showing our new design;

FIG. 2 is a rear elevational view thereof;

FIG. 3 is a left side elevational view with the right side

being a mirror image of same; and,

FIG. 4 is a bottom plan view thereof.

Fig. 4
